(57) **CLAIM**

The ornamental design for a tool box, as shown and described.

DESCRIPTION

FIG. 1 is a perspective view of a tool box showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 5;

FIG. 10 is an enlarged view of portion 10 shown in FIG. 6; and,

FIG. 11 is an enlarged view of portion 11 shown in FIG. 7; and,
FIG. 12 is an enlarged view of portion 12 shown in FIG. 8. The dashed broken lines in the drawings depict portions of the tool box that form no part of the claimed design. The dot-dash broken lines in the drawings depict boundaries of the enlarged portions that form no part of the claimed design.

1 Claim, 12 Drawing Sheets
